UNITED STATES PATENT OFFICE.

PETER RODGERS, OF PHILADELPHIA, PENNSYLVANIA.

DESIGN FOR A LOCK-CASE.

SPECIFICATION forming part of Design No. 30,314, dated March 7, 1898.

Application filed February 8, 1898. Serial No. 704,981. Term of patent 14 years.

To all whom it may concern:

Be it known that I, PETER RODGERS, a subject of the Czar of Russia, (having resided in the United States one year last past and having declared my intention of becoming a citizen thereof,) residing in the city and county of Philadelphia, State of Pennsylvania, have invented and produced a new and original Design for a Lock-Case, of which the following is a specification, reference being had to the accompanying drawings, forming part thereof.

The leading feature of my design for a lock-case is a body having peripheral rings and a conoidal point.

Figure 1 represents a side elevation of a lock-case embodying my design. Fig. 2 represents a longitudinal section thereof.

In the drawings, A designates the body of a lock-case, the same being of cylindrical form and having a conoidal point B and a series of rings C on the side of said body, projecting beyond the periphery thereof.

D designates a loop on the body of the case opposite to the point B.

Having thus described my invention, what I claim as new, and desire to secure by Letters Patent, is—

The design for a lock-case substantially as shown and described.

PETER RODGERS.
